UNITED STATES PATENT OFFICE.

GEORGE R. FOLDS, OF EVANSTON, ILLINOIS, ASSIGNOR TO FRANK B. COOK COMPANY, OF CHICAGO, ILLINOIS, A CORPORATION OF ILLINOIS.

LIGHTNING ARRESTER.

Application filed July 12, 1919. Serial No. 310,364.

To all whom it may concern:

Be it known that I, GEORGE R. FOLDS, a citizen of the United States, residing at Evanston, in the county of Cook and State 5 of Illinois, have invented new and useful Improvements in Lightning Arresters, of which the following is a full, clear, concise, and exact description, reference being had to the accompanying drawing, forming a 10 part of this specification.

This invention relates to lightning arresters and more particularly to improved means for electrically separating the line and ground springs of lightning arresters 15 used on low voltage electric circuits, such as telephone, telegraph and signal systems, to provide for high potential discharges.

Lightning arresters used for high potential discharges on low voltage electrical circuits 20 are equipped with means to provide a discharge gap which ordinarily takes either one of two forms in commercial practice. One of these constructions comprises two conducting plates, preferably constructed of 25 either carbon or copper and separated by a suitable dielectric, the high potential jumping from one plate to the other through an opening or openings provided in said dielectric. The other form comprises what is 30 ordinarily known as a saw-tooth arrester, in which a serrated or toothed edge is separated from a suitable ground plate, by the desired air space to insure the discharge of a determined minimum potential.

It is one of the objects of this invention 35 to provide an improved form of saw-tooth arrester construction, whereby the saw-tooth construction may be readily interchanged with the other construction heretofore referred to. This ready interchangeability 40 between these two constructions provides great flexibility, that is, it makes it possible to very readily convert an arrester from the one type to the other, that is, from the 45 block to the saw-tooth type. This flexibility is of great advantage to manufacturers, jobbers and also to the ultimate user. Thus for example, telephone companies that are 50 operating city as well as urban and rural telephone lines, usually find it practical to

use carbon block arresters at the sub-stations in the city and the saw-tooth lightning arresters in the urban and rural district. In the use of a standardized means for electrically separating the springs of 55 lightning arresters, it becomes possible to adapt any arrester of either the block or saw-tooth type and because of this ready conversion, the varying demands of operating practice can be very readily met with a 60 minimum amount of stock, since the standard spring equipment is readily adapted to either the block or saw-tooth arrester separation.

Another object of this invention consists 65 in the production of an improved and efficient form of saw-tooth arrester construction which may be readily assembled and which is low in manufacturing cost.

Other objects of the invention will be 70 become apparent from the following description, the accompanying illustrations and the appended claims.

For the purposes of description, several 75 embodiments of sub-station arresters used in telephone circuits are shown in the accompanying drawings. These are illustrative only, however, inasmuch as the invention is adaptable to any and all forms of lightning arresters used on low voltage circuits, such as the central station arresters, 80 aerial-wire arresters, pole cable terminal arresters and the like.

In the drawings:

Fig. 1 illustrates a view in perspective of 85 a substation arrester equipped with the saw-tooth spring separating means;

Fig. 2 is a side elevation thereof;

Fig. 3 is a section taken on the plane 90 represented by the line 3-3 of Fig. 2;

Fig. 4 illustrates a view in perspective of the arrester shown in Figs. 1 to 3 inclusive fitted with block type spring separating means.

Fig. 5 illustrates in perspective the 95 respective parts of the saw-tooth separating means shown in Fig. 1 disassociated from one another but positioned in the respective order in which they are combined when placed in position in the lightning arrester; 100

Fig. 6 is a similar view of the block arrester separating means;

Fig. 7 illustrates another form of saw-tooth arrester separating means; and

5 Fig. 8 is an illustration of one of the separating blocks illustrated in Fig. 7 with the parts disassociated from one another and positioned in the respective order which they assume when assembled in an arrester 10 mounting.

As illustrated in Figs. 1 to 3 inclusive, the arrester comprises a mounting base 10 fitted with apertures 11 and 12 adapted to receive screws for mounting the same. The 15 base 10 is also equipped with a central depression 13 adapted to receive the high potential protecting equipment. Mounted on the forward end of the mounting base 10 are the line terminals 14 and 15 and the 20 ground terminal 16. The line terminal 14 is electrically and mechanically connected to a spring 17 which extends rearwardly into the depression 13 at which point it is equipped with an upwardly extending arm 25 18 substantially at right angles to the mounting base 10. The terminal 15 is likewise mechanically and electrically connected to a spring 19 which extends rearwardly into the depression 13 and is also fitted with 30 an upwardly extending arm 20 normal to the mounting base. The ground terminal 16 is mechanically and electrically connected to a spring 21 which extends rearwardly into the depression 13 and is there fitted 35 with an upwardly extending ground plate 22.

The springs 17, 19 and 21 are preferably constructed of resilient metallic material, usually German silver. The upwardly extending arms 18 and 20 of the springs 17 and 19 respectively are shaped in such a manner as to exert a spring pressure in the direction of the ground plate 22 which is situated midway between these two upwardly extending spring arms 18 and 20.

40 Positioned between the spring arm 18 and the spring arm 20 and the ground plate 22 on each side of said ground plate, are the means utilized for mechanically connecting, but electrically separating each of these 45 springs from the ground plate.

The apparatus used for this purpose, illustrated in Fig. 1, comprises the saw-tooth equipment which is illustrated in detail in 55 Fig. 5. This equipment as there shown comprises a plate 25 fitted with lateral flanges 26 and 27. The flange 27 has a serrated or saw-toothed edge, as illustrated at 28. This plate is made of conducting material, 60 preferably sheet brass, and is equipped with the upset portions 29 and 30, which are adapted to properly guide and position the plate in either of the upwardly extending spring members 18 or 20.

65 Positioned between the flanges 26 and

27 of the plate 25 is a dielectric 31, which is composed of some suitable non-conducting material, preferably celluloid or mica.

Positioned between the flanges 26 and 27, above the dielectric 31 is a non-conducting 70 block 32. This block 32 has the lateral edge 33 which is next adjacent the serrated edge 28 of the flange 27 cut away so as to leave an open space between the serrated edge and the block 32. This cut away portion 75 is provided to present an increased area of the carbon block 34 next adjacent the non-conducting block 32 to the serrated edge 28. The carbon block 34 is positioned next to the ground plate 22 and in electrical contact therewith. The carbon block 34 is fitted with a central slot 35 whereby said block may be used either next adjacent the ground plate 22 or in connection with either the springs 18 or 20 in which case the slot 80 35 serves to position the block in its proper relationship with respect to the springs 18 and 20.

The flat surface of the carbon block 34 in contact with the non-conducting block 90 32 is of greater width than the width of the plate 25 and its lateral flanges 26 and 27, whereby a narrow ledge of carbon block surface will extend out beyond the serrated edge 28 of the plate, thereby facilitating 95 the discharge of the high potential, and to some extent preventing the concentration of the pitting action which results from the potential discharge.

When the various parts 25, 31, 32 and 35 100 are all assembled in position, as illustrated in Fig. 1, it will be evident that the carbon block 34 is in direct contact with the ground terminal 16 and that the plate 25 is in direct electrical contact with either the 105 line terminals 14 or 15 depending upon which side of the ground plate the apparatus is positioned. However, there is no electrical contact between the carbon block 34 and the plate 25 since these are insulated 110 from one another by the dielectric 31 and the non-conducting block 32. The block 32 is so designed that when it is positioned in the plate 25 between the flanges 26 and 27, the top face or surface of said block will 115 rest in substantially the same horizontal plane as the upwardly extending points of the serrated edge 28 of the flange 27.

When the dielectric 31 is placed in position under the block 32 between the flanges 120 26 and 27, it will be evident that the serrated edge will be drawn away from the horizontal plane in which the top surface of the block 32 is positioned. The dielectric 31 is given a thickness which is equal 125 to the separation desired between the tooth points of the serrated edge 28 and the carbon block 34 to provide for the discharge of the minimum potential at which the arrester is designed to operate. The dielec- 130

tric 31, consequently, is the means utilized to give the desired separation between the saw-toothed edge of the plate 25 connected to the line terminal and the flat surface of 5 the carbon block 34 connected to the ground terminal 16.

A dielectric is shown in this construction inasmuch as it has been standard practice 10 to use a dielectric to attain the desired separation between the ground and line blocks on arresters. It will be obvious, however, that the dielectric 31 could be readily dispensed with and the block 32 so proportioned that the thickness thereof would be 15 equal to that of the block 32 and the thickness of the dielectric 31. When thus designed, with this additional thickness, the block 32, when placed in position between the flanges 26 and 27, will give the desired 20 separation between the line plate 25 and the carbon ground block 34.

Fig. 1 shows the saw-toothed arrester block protecting means placed in position between the line and ground terminals. 25 When this apparatus has been thus placed in position to prevent foreign matter from reaching the springs and causing possible short circuits, the apparatus is covered with a cap 36 which rests on a ledge 37 provided 30 in the depression 13. The cap 36 is usually made of some conducting metallic material and to prevent accidental contact between the cap and the line and ground contact springs; the cap is usually lined with 35 an insulating sleeve 38.

In Fig. 4 the same mounting base is shown which is illustrated in Figs. 1 to 3 inclusive, but the arrester here shown is equipped with the standard carbon block 40 separating means in place of the saw-toothed separating means illustrated in Fig. 1.

The carbon block separating means comprises the three elements illustrated in a disassociated relationship in detail in Fig. 45 6. These elements consist of two carbon blocks 34 separated by a dielectric such as 39 or any other suitable commercial form of dielectric, well known to those skilled in 50 the art. Both of the carbon blocks used between each line spring and the ground plate, are identical in all respects to one another and to the carbon block 34 used with the saw-tooth protector to contact with 55 the ground plate 20.

In the arrester shown in Fig. 4, the minimum high potential for which the arrester is designed, will jump from the carbon block 34, which is electrically connected to 60 the line terminal through the perforations 40 in the dielectric, to the carbon block 34 connected to the ground plate 22. In the arrester illustrated in Figs. 1 to 3 inclusive, the minimum high potential for which the 65 arrester is designed, will jump from the

serrated edge of the plate 25 to the carbon block 34 associated with the ground plate 22.

It will be evident now from the foregoing description that the arrester shown in 70 Figs. 1 to 3 inclusive and in Fig. 4 are capable of receiving either, the saw-toothed electrical separating means consisting of the plate 25, the dielectric 31, the non-conducting block 32 and the carbon block 34, 75 or the carbon block separating means consisting of the two carbon blocks 34 and the dielectric 39. In other words, the arrester is very readily convertible from the one type to the other and the manufacturer, 80 jobber or the ultimate operating company, by maintaining in stock carbon blocks such as 34, dielectrics such as 39 and 31, and non-conducting blocks such as 32 and plates such as 25, are in a position to construct 85 out of standard arrester mounting bases, and their associated contact springs, either carbon block or saw-toothed discharge gap lightning arresters.

Figs. 7 and 8 illustrate another form of 90 ground and line spring arrester separating means. The mounting base and associated contact springs illustrated in Fig. 7 are the same shown in Figs. 1 to 3 inclusive. The ground spring and the line spring in this 95 instance, however, are separated electrically by a saw-toothed spark gap separating means illustrated in detail in Fig. 8. This separating means consists of a plate 40 fitted with lateral flanges 41 and 42, each of which 100 are serrated as indicated at 43 and 44 respectively. The plate 40 is also equipped with the upset portions 45 and 46 similar to that described in connection with the plate 25 illustrated in Fig. 5, adapted to 105 properly center the plate on either of the springs 18 or 20.

Positioned on the plate 40 which is constructed of conducting material, preferably sheet brass, is the dielectric 47. Placed directly above the dielectric 47 is the non-conducting separating block 48 fitted with the two lateral edge depressions 49 and 50 to provide for an increased discharge surface on the carbon block 51 for the serrated 110 edges 43 and 44. These lateral edge depressions 49 and 50 serve the same purpose as the cut away portion 33 illustrated in connection with the block 32 illustrated in Figs. 1 and 5. The carbon block 51 used in 115 connection with the arrester shown in Fig. 7 is fitted with a central slot 52 adapted to properly position the block on the line spring 18 or 20.

When the various elements or parts 125 shown in Fig. 8 are assembled in their relative operating positions, as shown in Fig. 7, it will be evident that the line terminals 14 and 15 are respectively connected to plates, such as 40, that the ground terminal 130

16 is connected to carbon blocks such as 51 and that the carbon blocks 51 are separated from the plates such as 40 by means of the dielectric 47 and the non-conducting separating block 48. The high potential in this construction will be discharged through the serrated edges 43 and 44 to the carbon block 51.

When it is desired to convert the spark gap separating means of the arrester shown in Fig. 7 from the saw-toothed type to the carbon block type, it is merely necessary to use two carbon blocks such as 51 separated by a suitable dielectric similar to 39 (Fig. 6) on either side of the ground plate. Consequently the spark gap separating means used with the arrester illustrated in Fig. 7 is likewise convertible from the carbon block type to the saw-toothed type or vice versa.

It now follows from the foregoing description that according to the teachings in this invention, lightning arresters may be readily constructed which may be readily converted to meet the varying demands of operating practice in telephone, telegraph and signalling systems, from either the carbon block to the saw-toothed type. It also follows that due to this flexibility and ready interchangeability, there is a very material saving in the amount of stock that must be carried to meet the varying conditions, since the equipment is so standardized that it can be changed at any time to meet either one of the two conditions desired.

Obviously, the invention is not limited to the specific embodiments thereto herein illustrated and described, but it capable of many variations and other applications within the spirit and scope of the invention as set forth in the following claims.

Having thus described my invention, what I claim as new and desire to secure by Letters Patent is:

45 1. In a lightning arrester, in combination, line springs and a ground plate placed in juxtaposition thereto, said springs being severally adapted to be mechanically interconnected but electrically separated from said plate by a pair of conducting blocks separated by a dielectric, and means for mechanically connecting and electrically separating each of said springs and plate comprising a conducting plate with a serrated electric discharge edge, said conducting plate being adapted for interchangeable insertion with one of said conducting blocks that may be received between each of said springs and plate.

60 2. In a device of the character described in combination, a metallic plate having a lateral flange, the edge of said flange being serrated, means integral with said plate adapted to properly position the plate in its operating position, a conducting block, and

a non-conducting means separating said block and said plate to provide the desired spark gap between said block and said serrated edge.

3. In a device of the character described in combination, a metallic plate having a lateral flange, the edge of said flange being serrated, means integral with said plate adapted to properly position the plate in its operating position, a conducting block, and a non-conducting means separating said block and said plate to provide the desired spark gap between said block and said serrated edge, said block being wider than said plate to provide a narrow ledge which extends out beyond the serrated edge of the said plate.

4. In a device of the character described in combination, a metallic plate having lateral flanges, one of said flanges having a serrated edge, means integral with said plate adapted to properly position the plate in its operating position, a non-conducting means positioned between said flanges, and a conducting means against which said non-conducting means is adapted to rest, said non-conducting means maintaining the desired separation between said serrated edge and said conducting means.

5. In a device of the character described in combination, a metallic plate having lateral flanges, one of said flanges having a serrated edge, a non-conducting means positioned between said flanges, and a conducting means against which said non-conducting means is adapted to rest, said non-conducting means maintaining the desired separation between said serrated edge and said conducting means and having a portion of its surface next adjacent said serrated flange cut away to expose a large surface of said conducting means.

6. A lightning arrester comprising a metallic plate having turned-over edges one at least of which is serrated to form a multiplicity of electric discharge paths, said plate incorporating integrally formed means for properly locating it in its operating position, a non-conducting member received in said plate between its turned-over edges and having an exposed surface that extends beyond the serrated edge of said plate, and a conducting member in contact with said exposed surface of said non-conducting member and presenting a discharge surface to said serrated edge.

7. A lightning arrester comprising a metallic plate having a turned-over edge which is serrated to form a multiplicity of electric discharge paths, said plate incorporating integrally formed means for properly locating it in its operating position, and a non-conducting member disposed on the side of said plate from which said over-turned edge extends, said non-conducting member hav-

ing an exposed surface subtending said serrated edge and projecting beyond the level thereof.

8. In a device of the character described in combination, a metallic plate having lateral flanges one at least of which is provided with a serrated edge, a separating means disposed between said flanges, a conducting means against which said separating means

is adapted to rest, and a dielectric adapted to be positioned between said separating means and said plate whereby a spark-gap separation may be effected between the serrated edge of said plate and the said conducting means.

In witness whereof, I have hereunto subscribed my name.

GEORGE R. FOLDS.
